METHOD OF AND MOLD FOR CASTING
VITREOUS WATER CLOSET BOWLSJoseph W. Pieslak and Raymond E. Crane,
Kittanning, Pa.

Application November 15, 1944, Serial No. 563,532

9 Claims. (Cl. 25—129)

1

This invention relates to hollow vitreous castings, such as water closet bowls, and the casting thereof from liquid clay slip.

Objects of the present invention are to provide for casting such an article in a new and improved manner so as to provide a new and improved product wherein joints are obviated in the bowl proper, the trapway and other parts of the casting; to enable the formation of the bowl and its associated trapway in the form of a single integral casting free from joints; to reduce the parts of the mold to the minimum number of parts; and to simplify the assembly and the taking apart of the mold and otherwise simplifying and improving the production of vitreous water closet bowls.

With these and other objects in view, the present invention consists in the combination and arrangement of parts as will be hereinafter more fully described, illustrated in the accompanying drawings, and particularly pointed out in the appended claims, it being understood that changes in the form, proportion, size and minor details may be made, within the scope of the claims, without departing from the spirit or sacrificing any of the advantages of the invention.

In the drawings—

Figure 1 is a vertical longitudinal sectional view of a water closet bowl mold of the present invention and showing the bowl casting therein;

Figure 2 is a vertical cross sectional view on the line 2—2 of Figure 1;

Figure 3 is a rear elevation of Figure 1 on a smaller scale;

Figure 4 is a fragmentary plan section on the line 4—4 of Figure 3;

Figure 5 is a detailed vertical sectional view of the combined back and plug member of the bowl;

Figure 6 is a fragmentary vertical sectional view of a top portion of the mold and the contained casting, the top member of the mold being removed, and a flushing rim fitted to the top edge of the casting;

Figure 7 is a fragmentary sectional view similar to Figure 1 and showing a modification;

Figure 8 is a rear elevation of Figure 7, on a smaller scale;

Figure 9 is a fragmentary plan section on the line 9—9 of Figure 7;

Figure 10 is a view similar to Figure 1 showing a modification in the bottom member of the mold;

Figure 11 is an elevation of the mold, on a smaller scale, turned over and resting on one of its side members;

Figure 12 is a view similar to Figure 11, the bot-

2

tom mold member and the upper side mold member being removed, and showing a slab lying against the top of the flushing rim; and

Figure 13 is an elevation of the casting, on a smaller scale, turned over from the position of Figure 12 with the flushing rim resting on the slab and with one of the side mold members in place preparatory to removal.

According to the embodiment of the present invention as shown in the accompanying drawings, the mold includes opposite duplicate upright wall members A and B, a base wall member C, and a top wall member D. The inner face of each upright mold wall member A and B is configured to define a part of the bowl, and upright side portions of the downleg 1 of the trapway and the upleg 2 of the trapway. The base wall member C has its top face configured in accordance with the desired configuration of the bottom of the casting and includes an upstanding hump or elevation 3, constituting in effect a core whose top and side surfaces are shaped to define portions of the casting.

The top wall member D of the mold rests upon the top edges of the upright side wall members A and B and is provided with a depending projection or boss 4, which may be integral with the top or otherwise, extending downwardly within the space defined by the side wall members A and B and constituting a core whose exterior surface is configured to give the desired shape to the inner surface of the bottom of the bowl and the inner upright surfaces thereof. The core 4 is spaced a suitable distance from the inner walls of the bowl portions of the side members A and B so as to receive therebetween the liquid clay slip employed to make the casting, as will be hereinafter explained. A pouring opening 5 of suitable size and configuration, is provided through the top wall member D at one side of the core 4, and having its lower open end in communication with the space between the core 4 and the inner faces of the side wall members A and B to facilitate the pouring of liquid clay slip into the mold. For draining the liquid clay slip from the mold, the bottom wall member C is provided with a drain opening 6 communicating with the bottom of the downleg portion 1 of the casting.

In Figures 1 to 5, inclusive, it will be seen that the wall portions of the casting which separate the downleg 1 from the upleg 2 are deposited or formed on a partition 7 which is in the nature of a plug carried as a part of a mold back wall member 8 which is arcuate in shape in a horizontal direction as best shown in Figure 4. This

back wall mold member rises from the base wall C and terminates short of the tops of the mold side wall members A and B, which sides are notched or cut away, as indicated at 9 to receive the arcuate mold back wall member 8. This combined plug and back wall member is provided with an outwardly and rearwardly directed portion 10, in the upper face of which is provided a gutter 11 leading to a drain opening 12 formed through the back wall member 8 immediately above the plug portion 7. To produce the usual downwardly extending jet channel 13, an upright groove or channel 14, shown in Figure 4, is provided in the inner faces of the back parts of mold side wall members A and B, and the member 8.

In employing the mold of the present invention, as embodied in Figures 1, 2, 3, 4 and 5, for casting a water closet bowl, the upright side wall members A and B of the mold are placed in an upright position upon the base wall C, the combined plug and back wall member 8 is then put in place and supported on the base wall C, after which these mold wall parts are secured together by the application of suitable clamps or other fastening means not shown. The top wall member D is then put in place and supported upon the top edges of the wall members A and B with the core 4 within the bowl-defining wall portions of the wall members A and B. Liquid clay slip is then poured through the opening 5 in the top D until all of the spaces between the several portions of the mold wall have become filled with the casting material. As usual, the mold wall members are made of plaster of Paris or other suitable water-absorbing material so that water will be absorbed thereby from that portion of the liquid clay slip in contact with and adjacent to the mold parts to the end that liquid clay slip will adhere to the mold parts and thus build up a hollow casting of the configuration of the interior of the mold. It will, of course, be understood that the liquid clay slip will entirely fill the space between the cooperating parts of the mold, and that only a portion thereof will adhere to the mold walls and become hardened sufficiently to take on the desired configuration. When a desired bowl wall thickness has been deposited or collected upon the mold walls, which condition is determined by experience, the slip material which remains liquid is discharged or drawn off from the mold through discharge openings 6 and 12, thus leaving a hollow casting of a configuration defined by the mold walls.

It will be explained that preparatory to pouring the casting material into the mold, the drain openings 6 and 12 should be plugged and closed in any suitable manner; such plugs subsequently being removed when it is desired to discharge or drain material from the interior of the mold. It will, of course, be understood that the mold may be tilted, inverted or otherwise manipulated to facilitate the draining of the liquid casting material from the mold.

A suitable length of time should lapse between the pouring of the liquid casting material and the removal of the mold wall members from the casting in order to permit of sufficient moisture being absorbed from the casting by the walls of the mold until the casting has become hard enough to permit handling without breakage. When the casting has hardened to the desired extent, the top wall member D should be removed upwardly, thus exposing the inside of the cast bowl and the upper edge thereof. Thereupon,

as shown in Figure 6, any ordinary or preferred form of flushing rim 15 cast from liquefied clay slip should be placed in position on the top edge of the bowl and secured in place by means of the usual coating of sticking clay applied to either the edge of the bowl or the rim, or both.

When the rim has hardened sufficiently and a satisfactory adherence has taken place between the rim and the top edge of the casting, the mold is turned down so as to rest upon one of its side wall members, the mold being shown in this position in Figure 11 with one side wall member B resting upon some suitable support. The back wall member 8 and plug 7 are then removed. The next step is to remove the bottom mold wall member C horizontally, the casting being supported within the side mold wall members A and B. After removing the bottom member C, the uppermost side wall member, A in the present instance, is removed upwardly, thus leaving the casting supported upon the mold side wall member B as shown in Figure 12. The next step is to apply a slab or bat 16 in an edgewise upright position against the top of the rim 15, as shown in Figure 12, and then the casting, together with the side mold wall member B and the slab 16 are turned to the position shown in Figure 13 so as to support the casting on the rim 15 which would in turn be supported upon the bat or slab 16. The mold side wall member B, which is now in an upright position, may be removed horizontally away from the casting. The casting is then permitted to stand still until it has dried to a satisfactory condition, after which the casting is smoothed and finished to a condition such that it may be fired in a kiln.

From the foregoing description, it will be understood that the bowl proper together with its trapway is an integral casting formed of clay slip and without any joints whatsoever. There is, of course, a joint between the top edge of the bowl proper and the flushing rim, but there are no joints in the bowl proper and in the trapway.

In Figure 1 of the drawings, the discharge opening 17 of the bowl leading into the trapway may be produced by applying shellac to the surface of the core 10 which is to define this opening, the shellac operating to prevent the accumulation of the casting material on this coated surface portion of the core 4. If desired, the shellac may be omitted and the casting material permitted to collect on the surface of the core 4 where the discharge opening should be, and thereafter the material may be removed by cutting before complete hardening of the material.

In Figures 7, 8 and 9, there has been shown a slight modification wherein the back mold wall member 8 is omitted, and the upright side mold wall members A and B extend in full length from the base to the top of the mold, the meeting edges of the mold wall members A and B, at the back of the mold, being provided with registered notches or recesses to receive a plug or partition 7' corresponding to the plug or partition 7 of Figure 1. This plug has a rearward extension 10' and a gutter 11' similar to what is shown in Figure 1. As well shown in Figure 8, the meeting edges of the side mold wall members A and B are provided with registered notches 18 which also register with the open top of the inner end of the gutter 11 and define a drain opening 19 leading into the gutter whereby liquid clay slip may be drained from the upleg portion 2 and the jet passage 13. Otherwise, the embodiment of the invention, as shown in Figures

7, 8 and 9, is the same as that shown in Figures 1 to 5, inclusive, and the method of removing the mold members is the same as that described for the embodiment shown in Figures 1 to 5, inclusive.

Another embodiment of the invention has been shown in Figure 10 of the drawing wherein the bottom wall member C is provided with an upwardly inclined opening or passage 20 to receive a plug 21 which is of a shape and dimension to extend upwardly beyond the top of the mold bottom wall C and define the lower wall of the upleg 2 and the inner wall of the downleg 1. The opening 20 is so disposed and the plug 21 is so configured that it may be withdrawn from between the adjacent walls of the legways 1 and 2 without damaging said walls preparatory to removing the mold bottom wall C from the casting. Otherwise, the method of employing the mold of Figure 10 is the same as that described for the other forms of the invention.

What we claim is:

1. In a mold for casting water closet bowls having a trapway including an upleg and a downleg, the combination of a base mold wall having its top configured to form the base of a bowl structure, upright side wall members supported on the base wall and configured to define sides of the bowl, a top mold wall member supported upon the top edges of the side mold wall members and having a depending core portion spaced from the upright side mold wall members to define the inner face of the bowl, and a plug member insertable and removable through a wall of the mold and having a portion disposed between the core and the base wall member said plug being spaced from the core to define an upleg between the core and the plug, and also spaced from the front and bottom walls of the mold to define a downleg between said parts, the bottom of the core, the front wall of the mold and the inner end portion of the plug being spaced to define an elbow passage between said parts and connecting the inner ends of the upleg and the downleg.

2. In a mold for casting water closet bowls having a trapway including an upleg and a downleg, the combination of a base mold wall having its top configured to form the base of a bowl structure, upright side wall members supported on the base wall and configured to define sides of the bowl, a top mold wall member supported upon the top edges of the side mold wall members and having a depending core portion spaced from the upright side mold wall members to define the inner face of the bowl, and a plug member insertable and removable through an upright wall of the mold and having a portion disposed between the core and the base wall member said plug being spaced from the core to define an upleg between the core and the plug, and also spaced from the front and bottom walls of the mold to define a downleg between said parts, the bottom of the core, the front wall of the mold and the inner end portion of the plug being spaced to define an elbow passage between said parts and connecting the inner ends of the upleg and the downleg.

3. In a mold for casting water closet bowls having a trapway including an upleg and a downleg, the combination of a base mold wall having its top configured to form the base of a bowl structure, upright side wall members supported on the base wall and configured to define sides of the bowl, a top mold wall member supported

upon the top edges of the side mold wall members and having a depending core portion spaced from the upright side mold wall members to define the inner face of the bowl, and a plug member insertable and removable through the mold base wall member and having a portion disposed between the core and the base wall member to define the lower side of the upleg and the inner side of the downleg of the trapway.

10 4. In a mold for casting water closet bowls having a trapway including an upleg and a downleg, the combination of a base having its top configured to form the base of the bowl structure, upright side members supported upon the base and configured to define sides of the bowl, a top resting upon the top of the side members and having a depending core portion spaced from the upright side members to define the inner face of the bowl, and a plug lying in the space between the base and the core and dividing said space into an upleg and a downleg of a trapway, said plug carrying a back member to define a portion of the back of the bowl, the upright side members being notched to receive the said back member.

15 5. In a mold for casting water closet bowls having a trapway including an upleg and a downleg, the combination of a base mold well having a top configured to form the base of the bowl structure, upright side wall members resting upon the base wall and configured to define sides of the bowl, a top mold wall member resting upon the tops of the side wall members and having a depending core portion spaced from the upright side mold wall members to define the inner face of the bowl, the base mold wall member having an opening extending therethrough, and a removable plug extending through said opening and having a portion projecting into the space between the core and the base wall member and defining the lower wall of the upleg and the inner wall of the downleg of the trapway of the bowl.

20 6. The herein described method of casting water closet bowls comprising the steps of assembling opposite side mold members upon a base, applying a top member having a depending core portion to define the inner wall of the bowl, inserting a plug member into the space between the core and the base member in position to define an upleg between the core and the plug and also to define a downleg between the front and bottom of the mold and the adjacent side of the plug, filling the spaces between the mold members with liquid clay slip and permitting the latter to adhere to the inner walls of the mold, removing surplus liquid clay slip from the mold, removing the top of the mold upwardly, turning the mold and supporting it on one side thereof, removing the plug member, removing the bottom member of the mold, removing the upper side mold member laterally from the casting, turning the casting and supporting it on the top thereof, and then removing the remaining mold side member.

25 7. The herein described method of casting water closet bowls, comprising the steps of assembling opposite side mold members upon a base, applying a top member having a depending core portion to define the inner wall of the bowl, inserting a plug member into the space between the core and the base member in position to define an upleg between the core and the plug and also to define a downleg between the front and bottom of the mold and the adjacent side of the plug, filling the spaces between the mold

members with liquid clay slip and permitting the latter to adhere to the inner walls of the mold, removing surplus clay slip from the mold, removing the top of the mold upwardly, sticking a pre-cast flushing rim upon the top edge of the casting, turning the mold and supporting it on one side thereof, removing the plug member, removing the bottom member of the mold, removing the upper side mold member laterally from the casting, turning the casting and supporting it on the top thereof, and then removing the remaining mold side member.

8. In a mold for casting water closet bowls having a trapway including an upleg and a downleg, the combination of a base having its top configured to form the base of a bowl structure, upright side members supported on the base and configured to define sides of the bowl, a top supported upon the top edges of the side mold members and having a depending core portion spaced from the upright side members to define the inner face of the bowl, and a plug member insertable and removable through a wall of the mold and disposed between the core and the base member and inclined upwardly towards the closed front of the mold from the place of insertion through a wall of the mold and terminating short of the closed front wall of the mold, said plug being spaced from the core to define an upleg between the core and plug and also spaced from the front and bottom walls of the mold to define a downleg between said parts,

the bottom of the core, the front wall of the mold and the inner end portion of the plug being spaced to define an elbow passage between said parts and connecting the inner ends of the upleg and the downleg.

9. In a mold for casting water closet bowls having a trapway including an upleg and a downleg, the combination of a base having its top configured to form the base of a bowl structure, upright side members supported on the base and configured to form sides of the bowl, a top supported upon the top edges of the side mold members and having a depending core portion spaced from the upright side members to define the inner face of the bowl, and a plug member insertable and removable through the upright back wall of the mold and disposed between the core and the base member to define the lower side of the upleg and the inner side of the downleg of the trapway.

JOSEPH W. PIESLAK,
